[57] CLAIM

The ornamental design for a spool faceplate for a fishing reel, as shown and described.

DESCRIPTION

FIG. 1 is a perspective view of a spool faceplate for a fishing reel showing my new design.

FIG. 2 is an elevational view of one side thereof.

FIG. 3 is a front elevational view thereof.
Any broken line illustration in the drawing disclosure is not a part of the design sought to be patented and is present to denote the nature and environmental use of the claimed design.

FIG-1-FIG-2-
